By Charles J. Schmidt,
Atty.

UNITED STATES PATENT OFFICE.

WILLIAM T. HOLDEMAN, OF CHICAGO, ILLINOIS.

ADJUSTABLE CONNECTION FOR SWITCHES.

1,270,824.

Specification of Letters Patent.

Patented July 2, 1918.

Application filed December 14, 1916. Serial No. 136,848.

To all whom it may concern:

Be it known that I, WILLIAM T. HOLDEMAN, a citizen of the United States, and a resident of Chicago, in the county of Cook and State of Illinois, have invented certain new and useful Improvements in Adjustable Connections for Switches, of which the following is a specification.

My invention relates to an improved adjustable connection for switches particularly adaptable for connecting switch points with the operating train from a local switch stand or from a tower.

In the operation of switches the throw of the switch lever and connecting train is usually greater than the necessary throw of the switch to open or closed position and means must be provided to adjust or compensate for such difference. In Patent No. 20 791,622 issued June 6, 1905, to myself and others, adjusting mechanism for this purpose is shown but this mechanism is not as efficient as it might be and my present invention may be considered as an improvement thereover. In the arrangement of the patent the end of the operating train from the switch stand or tower is in the form of a head shiftable between adjustable abutments connected with the switch by means 30 of which adjustment can be made so that shifting of the operating train in one direction or the other will cause accurate and safe closure or opening of the switch, or safe and accurate operation of other devices such 35 as derails.

In the arrangement of the patent the abutments are in the form of plugs threaded into the ends of a housing secured to the tie-rod connecting the switch points, the rod at the 40 end of the operating train extending through one of the plugs and terminating in a head within the housing. Switch points or switch rails occasionally creep or shift longitudinally in which case the adjustment 45 housing will shift with reference to the switch stand or the operating train leading to a tower, and this will cause binding of the bar in the housing if no provision is made for axial play. One of the important 50 objects of my invention is therefore to improve the construction in order to permit axial play of the operating bar in the housing.

In the arrangement of the patent the adjusting plugs are polygonal at their outer ends to receive a wrench, while lock nuts requiring a larger wrench are used to lock

the nuts in adjusted position. Another important object of my invention is to provide improved lock nuts which can be turned with the same size wrench that takes the ends of the adjusted plugs.

On the accompanying drawing construction and arrangement is shown which embodies the above and other features of my invention. On this drawing—

Figure 1 is a perspective view showing the application of my adjustable connecting device to a switch.

Fig. 2 is an enlarged vertical diametral 70 sectional view thereof.

Fig. 3 is an end view.

Fig. 4 is a side elevational view of one of the lock nuts, and

Fig. 5 is a view of the inner end of the 75 operating bar.

In Fig. 1, *r* represents the rails of a track and *p* the points of a switch, these points being connected together at their front end by a tie-bar *t*. *A* represents my improved 80 adjustable connecting device which is secured to the tie-bar *t* and into which extends the rod 10 which is connected to be operated from a local switch stand or from a tower.

The device comprises a cylindrical housing 11 having the lateral extension *e* by means of which it may be secured to the switch or other device to be controlled. The ends of the housing are of reduced diameter and internally threaded as indicated at 12 90 and 13 for receiving the adjustable abutment plugs 14 and 15. The rod 10 extends through the bore 16 of the plug 14 and terminates in the abutment head 17. As the rod 10 is shifted longitudinally from the 95 switch stand or tower the head 17 is brought into engagement with the inner end of the respective plug to shift the switch or other device to be controlled, the relative movement between the head and housing determined by the adjustment of the plugs being such as will compensate for the difference in throw between the switch lever and the desired throw of the switch or other device. It has been found that the switch points 100 and the adjustable connecting attachment secured thereto are frequently shifted relative to the switch stand or operating train so that the axis of the connecting rod 10 will

tend to assume an angle with the axis of the 110 housing and this will of course immediately cause binding if no provision were made for preventing. I, however, prevent such binding by permitting lateral play of the rod 10

in the housing 11, and this I accomplish by making the diameter of the bore of plug 14 greater at its inner end than the diameter of the rod. In Fig. 2 the bore 16 is tapered 5 or conical and fits the rod 10 only at its outer end. This permits lateral play of the rod in the housing and assures free longitudinal shifting of the bar and prevents binding. The inner diameter of the inner 10 section of the housing 11 is sufficiently great to accommodate the head 17 during such lateral play of the rod 10.

The head 17 is preferably in the form of a nut applied to the threaded end 18 of the 15 rod and then rigidly secured by means of a pin 19. The nut is preferably cylindrical with its ends convexed to coöperate with the inner end of the plug 14 and the preferably convexed inner end of the plug 15 during 20 longitudinal shift and lateral play of the rod 10. To enable the nut to be applied to the threaded rod it is preferably given the opposed flattened sides 20 and 21 for receiving a wrench.

25 The outer ends 22 and 23 of the adjustable abutment plugs 14 and 15 are polygonal to receive a wrench. As shown on the drawing, the ends are hexagonal and preferably of a size to receive a standard track wrench so 30 that special tools will not be required for adjusting the plugs. To lock the plugs in adjusted position I provide lock nuts 24 and 25 of special construction. These lock nuts receive the projecting threaded ends of the 35 plugs and abut against the end flanges 26 and 27 of the housing 11. If these lock nuts were of the ordinary kind they would require a much larger wrench than the plugs. However, I provide radial lugs 28 on these 40 nuts of a width to receive the standard wrench so that the lock nuts can be turned with the same wrench that is used for the plugs. The width of the head 17 between its flat faces 20 and 21 can also be such as to 45 receive the standard wrench.

My improved adjustable connection has proven to be very efficient. The controlling parts are all within and protected by the housing 11 and rain, snow or dirt cannot enter to interfere with the proper movement 50 and setting of the switch or other device to be controlled. By means of the standard wrench all adjustment, setting and locking can be made and owing to the lateral play 55 of the connecting rod within the housing, there can be no binding.

I do not, of course, desire to be limited to the exact construction and arrangement shown and described as modifications are no 60 doubt possible which would still come within the scope of the invention.

I claim as follows:

1. In an adjustable connector of the class

described, the combination of a housing having its ends internally threaded, threaded 65 abutment plugs adjustable in said ends, one of said plugs having a passageway therethrough of greater diameter at the inner end than at the outer end, a rod extending through said passageway and fitting the 70 outer end thereof, and a head at the inner end of said rod for coöperating with said abutment plugs during relative movement of the rod and housing.

2. In a connector device of the class de- 75 scribed, the combination of a housing having a passageway therethrough threaded at its ends, abutment plugs adjustable in said ends and extending part-way into said housing, one of said plugs having a passageway 80 therethrough, and a rod extending through said passageway to shift longitudinally therein, a head at the inner end of said rod for coöperating with said abutment plugs, said passageway through said plug being of increasing diameter inwardly whereby said rod may have lateral play in said housing.

3. In a connecting device of the class de- 85 scribed, the combination of a housing having a passageway therethrough, abutment 90 plugs longitudinally adjustable in said ends and extending a distance therein to leave a space between their inner end, one of said plugs having a passageway therethrough, a rod extending through said plug passageway, a head at the inner end of said rod for 95 coöperating with the abutment plugs to limit the relative longitudinal movement of said rod and housing, said plug passageway increasing in diameter toward its inner end 100 and said head being of less diameter than said housing interior whereby said rod is free to swing laterally with reference to said housing.

4. In a connector device of the class de- 105 scribed, the combination of a cylindrical housing, plugs in the end of said housing separated a distance at their inner ends to leave an interior chamber, one of said plugs having a passageway therethrough, a rod 110 extending through said plug passageway, an abutment head on the inner end of said rod for coöperating in said interior chamber with the inner ends of said plugs, the di- 115 ameter of said passageway in one dia- 120 meteral plane being that of the rod and the diameters at other parts of the passageway being larger whereby said rod is free to swing laterally with reference to said housing during longitudinal movement of the rod.

In witness whereof I hereunto subscribe my name this 6th day of December, A. D. 1916.

WILLIAM T. HOLDEMAN.
